UNITED STATES PATENT OFFICE.

WILLIAM HERBERT S. HAMILTON, OF PITTSBURG, PENNSYLVANIA.

DESIGN FOR A GAS-BURNER.

SPECIFICATION forming part of Design No. 35,325, dated November 26, 1901.

Application filed October 10, 1901. Serial No. 78,277. Term of patent 3½ years.

To all whom it may concern:

Be it known that I, WILLIAM HERBERT S. HAMILTON, a citizen of the United States, residing at Pittsburg, in the county of Allegheny and State of Pennsylvania, have invented and produced a new and original Design for Gas-Burners; and I do hereby declare the following to be a full, clear, and exact description of the same, reference being had to the accompanying drawing, forming a part thereof.

This invention relates to gas-burners, and especially those in which incandescent mantles are used.

15 In the accompanying drawing, forming part of this specification, the invention is shown in perspective view.

As shown in the drawing, the leading or material features of the design are the vertically-disposed pipes A, united at their upper ends by the elbow-shaped sections or portions O and the T-shaped section or portion P, interposed centrally between the sections O, and at their lower ends by the elbow-shaped section B, having a vertical cylindrical portion C rising centrally therefrom and having 25 a series of slots or openings Q. Depending

from the elbow-section B is a cylindrical portion R. Mounted upon the cylindrical portion C is a bell-shaped portion D, and also 30 surmounted upon the cylindrical portion C and having portions interlocked or interposed with the pipes A is an enlarged portion or head E, with a series of cylindrical portions F rising vertically therefrom. Rising from a 35 projection L on the elbow-shaped section B is a smaller pipe K, having a bend at its upper end extending over the enlarged portion or head E and toward the center thereof and then extending upwardly above said head a 40 short distance. An annular or ring portion H is mounted upon the depending cylindrical portion R of the elbow-shaped section B, and depending from said portion B is a stem S, having a head N.

45 What I claim is—

The design for a gas-burner substantially as shown and described.

In testimony whereof I affix my signature in presence of two witnesses.

WILLIAM HERBERT S. HAMILTON.
